UNITED STATES PATENT OFFICE.

WILFRED STRAW, OF WATERBURY, CONNECTICUT, ASSIGNOR TO THE OAKVILLE COMPANY, OF SAME PLACE.

DESIGN FOR A PIN-PACKAGE CONTAINER.

SPECIFICATION forming part of Design No. 28,971, dated July 5, 1898.

Application filed December 22, 1897. Serial No. 663,101. Term of patent 7 years.

To all whom it may concern:

Be it known that I, WILFRED STRAW, of Waterbury, county of New Haven, State of Connecticut, have invented and produced a 5 new and original Design for a Pin-Package Container, of which the following is a specification, reference being had to the accompanying drawing.

The design is illustrated in the accompanying drawing, in which the figure is a perspective view of a pin-package container embodying the present design.

The pin-package container A is mounted on a base B and is provided with a series of

projections or fingers C along its upper edge, 15 which gives the container a characteristic appearance.

The design provides an attractive pin-package container which presents a characteristic and distinguishing appearance to the eye. 20

What I claim is—

The design for a pin-package container substantially as shown and described.

WILFRED STRAW.
